(57) CLAIM

I claim the ornamental design for a shower head cover, as shown and described.

DESCRIPTION

The claimed shower head cover may be placed over an existing shower head in an existing shower enclosure, or a variety of shower heads may be used, and installed inside the shower cover upon installation in a newly constructed shower stall.

FIG. 1 is a left side view of shower head cover showing my new design.

FIG. 2 is a rear view thereof.

FIG. 3 is a front view thereof.

FIG. 4 is a right side view thereof.

FIG. 5 is a top view thereof; and,

FIG. 6 is a bottom view thereof.
